United States Patent Office.

HENRY I. BRUNNER, OF NAZARETH, PENNSYLVANIA.

Letters Patent No. 91,515, dated June 22, 1869.

IMPROVEMENT IN BOILER-FEEDERS.

The Schedule referred to in these Letters Patent and making part of the same.

To all whom it may concern:

Be it known, that I, HENRY I. BRUNNER, of Nazareth, in the county of Northampton, and State of Pennsylvania, have invented a new and useful Improvement in Steam-Boiler Feeders; and I do hereby declare that the following is a full, clear, and exact description thereof, which will enable others skilled in the art to make and use the same, reference being had to the accompanying drawings, forming part of this specification.

This invention relates to a new and improved device for supplying steam-boilers with water, whereby many of the uncertainties and dangers of the ordinary force-pumps are avoided.

This invention consists in an arrangement for passing the feed-water to the boiler, by means of a transversely-perforated rotating valve, in such a manner that the feed-water falls into the boiler by its own gravity when the water in the boiler is low, or when there is a deficiency. When there is a sufficient supply of water in the boiler, there is no discharge by the cock, as will be hereinafter more fully described.

The accompanying drawing represents the arrangement attached to the boiler, partly in section.

A represents the boiler.

B is a chamber in which the valve rotates, and which is in communication with both the steam and water-spaces of the boiler.

C is the pipe connecting with the steam-space, and D is the pipe connecting with the water-space of the boiler.

E is the rotating valve.

F is the supply-pipe.

The valve E has an orifice, g, through it, into which orifice the water is introduced from the supply-pipe, and then transmitted to the boiler. As seen in the drawing, it is in communication with the supply-

pipe, or in a horizontal position. When it assumes a vertical position in the course of its rotation, the water it contains is subjected to the boiler-pressure, or to an equal pressure from each of the pipes C and D. The water, being thus balanced in the valve, will fall by its own gravity into the water-pipe D, if the water has fallen below the water-line H, or if there is a deficiency of water in the boiler.

Should there not be a deficiency, or should the water be up to the water-line, there would be no discharge from the valve, as the water it contains would be balanced.

The valve may be rotated by a belt, as indicated in red color in the drawing, or by gearing, or be actuated in any convenient and suitable manner.

I is a stop-cock in the supply-pipe F.

J and K are stop-cocks in the pipes C and D.

L is a small cock in the supply-pipe for letting off air, when starting the valve.

It will thus be seen that the boiler is supplied with a constant and uniform quantity of water, without forcing the water against the boiler; as it is where a force-pump is used; and that the pressure on the valve being balanced, the valve will rotate without any injurious amount of friction.

Having thus described my invention,

I claim as new, and desire to secure by Letters Patent—

The arrangement of the transversely-perforated valve E, in relation to the supply-pipe F and pipes C and D, respectively communicating with the steam and water-spaces of the boiler A, substantially as herein specified.

HENRY I. BRUNNER.
